VESSEL CHARGING APPARATUS

Harry L. McFeaters, New Castle, Pa., assignor to Pennsylvania Engineering Corporation, New Castle, Pa., a corporation of Pennsylvania

Application April 4, 1956, Serial No. 576,065

6 Claims. (Cl. 266—34)

This invention pertains to apparatus for processing or refining metal and particularly, to apparatus employed for feeding gas such as oxygen into a vessel in the oxygen process of steel making.

A phase of my invention deals with guide and clamp means for a tube supplying gas to a converter or refining vessel and to means which will close and open about the tube to support and release it during processing of material in the vessel.

This application is a continuation-in-part of my co-pending application Serial No. 507,631, filed May 11, 1955, and entitled "Charging Apparatus." In the disclosure of such application, I have discussed a process of steel making which involves introducing oxygen gas through a lance or tube downwardly into a processing vessel through its open mouth. In this manner, the charge is quickly and effectively refined. In such application, I have also disclosed the construction of a suitable tube or lance and of an overhead hoist or crane structure for employment with clamping apparatus.

It is contemplated that such an overhead structure will be employed with the improved guide and clamp means of the present invention. It will also be noted that a lance or tube (such as disclosed in my co-pending application) may be associated with and supported by apparatus of the present invention.

In employing an oxygen lance or blower tube, it is important to locate its discharge or lower end in a suitable relationship with the charge of material and with respect to the refining vessel. That is, the tube should be positioned so that it will not be burnt out in a short time, but such that the oxygen stream will effectively refine the metal in a minimum time and with a minimum of pick-up of deleterious gases or substances. The lance or tube should be located sufficiently below the mouth of the vessel to prevent the aspiration of air and thus, the build-up of nitrogen within the batch.

In employing a lance or oxygen tube in connection with a converter vessel, as well as with an associated collector hood for the hot gases and fumes, means must be provided for opening and closing the guiding and clamping means, for swinging it out of the way when the hood is to be used or the converter is to be charged, and for retaining it in a desired vertical and centered relationship within the vessel during the refining or blowing step. I have determined that the clamping and guiding means or apparatus should be positive in its holding action and easily releasable, but at the same time, should grip with a sensitive and substantially uniform gripping action, such as to avoid misaligning the tube or in introducing unnecessary stresses or strains which may tend to distort it under the intense heat to which it may be subjected.

It has thus been an object of my invention to provide an improved form of charging or processing apparatus for a refining vessel.

Another object has been to devise a so-called lance clamp having an improved operating action and an im-

proved holding or clamping action with respect to the lance;

A further object of my invention has been to provide a clamp apparatus which is constructed to provide substantially an even grip at its top and bottom portions, which is adjustable in substantially all directions, and is flexible in its utilization;

These and other objects of my invention will appear to those skilled in the art from the description and the showing of an illustrated embodiment thereof.

In the drawings,

Figure 1 is a top plan view of my apparatus of my invention showing its relative positioning with respect to a processing vessel and an exhaust hood for the mouth thereof;

Figure 2 is a side elevation of clamp apparatus or structure of Figure 1 and on the scale of such figure, illustrating it in a guiding and positioning relationship with respect to a lance tube; the full lines show the apparatus in its down or operating position and the dot and dash lines show it in a raised or upwardly-swung withdrawn position;

Figure 3 is a top plan view on an enlarged scale with respect to Figures 1 and 2; it shows clamping jaws in a closed relationship and a tilting adjustment of a frame or housing for the clamping apparatus;

Figure 4 is also a top plan view of the apparatus of my invention on the same scale as Figure 3, showing its clamping jaws in a closed position and its housing or frame in a substantially aligned relationship with respect to its support deck; it will be noted that in Figure 3, a swing adjustment has been made between the housing and the deck support to provide a substantially oblique relationship;

Figure 5 is a front end elevation taken along the lines V—V of Figures 1 and 4 and of the scale of Figure 4;

Figure 6 is a top plan view similar to Figure 4, but showing the clamping jaws in a fully open relationship and the corresponding positioning of the operating parts for such jaws;

Figure 7 is an end view in elevation taken along the line VII—VII of Figure 4 and on the same scale as such figure;

Figure 8 is a fragmental section taken along the line VIII—VIII of Figure 4 and on the same scale as such figure; and

Figures 9, 10 and 11 are fragmental sections taken respectively along the lines IX—IX, X—X, and XI—XI of Figure 4 and on the same scale as such figure.

The apparatus 10 shown has a clamping platform which is vertically swingable at its inner ends on or about a hoist or crane mechanism 11. The apparatus may be lifted or swung away from a refining or converting vessel 13 by the crane, itself, and which may be lowered to a substantially horizontal and cooperating relationship with an oxygen lance tube 12 to securely and effectively hold and align the tube to extend within the mouth or opening of the vessel. The apparatus is constructed to provide a more positive clamping action on the lance and is adjustable in its positioning for take-up and wear as well as for a proper aligned relationship, and its various parts, including its motor, are adjustable so as to meet all requirements of such a utilization. The lever or operating arrangement for actuating the jaws provides a toggle action for a firm grip on the lance. A hinged or swinging platform has a deck so that it is accessible for inspection by an operator.

Referring to Figures 1 to 6 of the drawings, and particularly to Figure 6, the arrow line *a* shows the path of movement of the lance 12 with respect to the jaws and *b* shows the 50° swing or arc represented between the opened and closed positions of the jaws. Referring par-

ticularly to Figure 1, 10 represents the apparatus of my invention taken as a whole, 11 represents the crane or hoist structure or frame, such as more particularly disclosed in my above-mentioned co-pending application, and 12 (see Figure 2) discloses the oxygen lance or tube assembly. In Figure 1, the dot and dash line 13 discloses the outline of an oxygen vessel to show the positioned arrangement of the clamping apparatus with respect to and above the vessel. An exhaust hood 14 is also illustrated and is shown as having a flange 15 and an offset 15a to bypass the jaws of my construction in its movement into and out of a gas-receiving relationship with respect to the mouth of the converter vessel 13.

Referring to Figures 1 and 2, a forwardly-projecting horizontal beam member 16 of the hoist frame structure 11 is adapted to project forwardly beyond a pair of vertical upright beam members 17 of the same hoist structure 11. As shown in Figure 1, the beams 17 are positioned in a spaced-apart relationship with each other and each carries secured thereon a fixed bracket structure 18. The open or bifurcated end of the bracket structure 18 has a pivot pin 19 projecting through its U-shaped fingers to cooperate with and pivot or swing-mount a sleeve 21. The pivot sleeve 21 is integrally carried by an under frame member 20a of a side platform 20 of the apparatus of my invention. Structural frame members, including diagonally-forwardly-projecting I-beam under member 20b, under member 20c, and cover or deck plate 20d, are secured together as by welding to provide the side platform 20.

As shown in Figures 1 and 2, the forwardly-projecting I-beam member 20b has an eyelet portion 26 to which a suspension chain and turn-buckle assembly 27 is linked. The upper end of the assembly 27 is pivotally connected at 28 to the beam member 16 to support the apparatus 10 in its horizontal or normally-positioned relationship of Figure 2.

Also, as shown in Figure 1, the apparatus 10 has an opposite side platform 23 whose under structural member 23a has a swing or pivot sleeve 24 integrally secured thereto and cooperating with pin 19 to swingably suspend it from between the U-shaped fingers of the second fixed bracket structure 18. The platform 23 is constructed to support a man and may be made up of suitable reinforcing or under frame members, such as diagonal member 23b which is secured between members 20b and 23a to form an integral structure therewith. A cover or deck plate member 23d is secured on the structural members and not only provides a platform for inspection by an operator, but also provides a platform for the adjustable support of my clamping apparatus and its upper housing, frame or platform structure 33. The latter provides an adjustable deck or platform for interleaving clamping jaws or fingers, for their operating connections, and for actuating or motivating means.

As shown in Figures 4 to 6 and 8, a secondary platform or plate member 30 carries the structure 33, rests on the lower deck member 23d of the structure 23, and is adjustably secured thereto by bolt assemblies 31. As shown particularly in Figures 3, 4 and 6, the bolts 31 may be loosened to slide the member 30 along slots 30a to provide a wide range of endwise horizontal adjustment between the members 23d and 30.

Since the secondary platform member 30 carries an acutating motor 70, operating connections, jaws, etc., of my apparatus, it is apparent that a lengthwise adjustment of the member 30 by means of the bolts 31 and slots 30a with respect to the deck member 23d will adjust the relationship of all the apparatus 33 or means carried on the member 30. As shown in Figure 4, upright support members 37a, 37b and 37c are welded to and space the plate members 34 and 35.

The endwise adjustment of and the secure holding of an adjusted relationship of the secondary platform mem-

ber 30 is accomplished by a threaded, longitudinal adjustment screw 45, see Figures 4 and 6. The head or inner end of the screw 45 is secured as by weld metal to an upright end plate 46 which is welded to a back edge of the platform member 30 to project upwardly as an integral part thereof. An L or angle bracket 44 is secured to project upwardly from the primary deck 23 and has a hole therein to loosely receive the stem 45. Adjustment is effected by means of a pair of opposed threaded nuts 47 which cooperate with the bracket 44 for this purpose.

The upper operating housing or frame 33 is made up of a lower plate member 34 and an upwardly spaced-apart and similarly horizontally-extending upper plate member 35. The lower member 34 rests directly on the secondary platform 30 and is pivotally mounted thereon, as shown in Figures 6 and 8, by a pivot-pin bolt assembly 38. Since the lower threaded end of the pin 38 is secured to the platform member 30, and since its upper enlarged portion receives the lower member 34 of the housing 33, it will be apparent that the housing 33 may be swung or laterally-adjusted about the pivot pin as desired. In this connection, I have provided a pair of lateral adjustment screws 41 and 42.

One screw 41 on one side of the housing 33 has a bolt head or wrench flat 41b for adjusting it. It has a threaded stem portion 41a that adjustably projects through an upright mounting block 40a, carries an adjustment lock nut 41c, and has a clamping head portion 41d at its inner end to abut against a vertical abutment piece 36. The mounting plate 40a is secured (see Figure 9) as by weld metal to the secondary platform member 30 as is a similar mounting plate member 40b for opposed adjustment screw 42. The piece 36, as shown in Figure 9, is secured as by weld metal between the upper and lower members 35 and 34 of the housing 33.

Adjustment screw 42 has a threaded outer end portion 42a that adjustably extends through mounting block 40b, and is locked in an adjusted relationship by nut 42c. Inner abutment end portion 42d is adapted to oppose the portion 41d of the adjustment member or element 41 and abut against the abutment member 36. A study of Figures 8 and 9 from the standpoint of Figures 3 and 4 discloses that the stems 41 and 42 may be adjusted to hold the housing 33 in a fully aligned position, such as shown in Figure 6, or to swing it on its pivot pin 38 to form a diagonal relationship, such as shown in Figure 3. The end of the element 42 will preferably have a slot to receive a screwdriver.

The apparatus of my invention has a pair of fixed jaws 48a and a pair of swing or moving jaws 50a which are adapted to close with respect to each other and at their concave portions 48b and 50b, receive and clamp a lance tube such as 12. Referring particularly to Figures 4 and 5, the fixed jaws 48a are securely mounted in a vertically spaced-apart relationship with respect to each other on a vertical cross bar or head 48. The bar 48 is secured as by weld metal from inner ends of the upper and lower members 35 and 34 of the structure 33.

On the other hand (see Figures 6 and 7), the swing jaws 50a are bifurcated at their inner end portions 50c to fit over a vertical head or cross bar member 49. Pin and cotter pin assemblies 51 pivotally mount the bifurcated portions of the fingers on a bar member 49. A saddle 52 centrally fits over the vertical bar member 49 and is pivotally mounted thereon by pin and cotter pin assembly 54. The saddle member 52 has a pair of threaded mounts 52a, each of which receives a screw adjusted assembly 53. The latter are employed to equalize and tighten the jaws as linkage wears, in that (as shown in Figure 7) the inner ends of the bolts 53 abut against the bar member 49. In this way, the pivoted relationship may be adjusted about the pin assembly 54 by means

of the adjustment bolts 53 after tightening or position-lock nuts 53a have been loosened.

The saddle member 52 has a pair of vertically spaced-apart angularly-projecting mounting arm portions 52b which at their ends (see particularly Figures 4, 5, 6 and 10) carry a fixed pivot or stub shaft 57. The shaft 57 is at its upper and lower ends journaled within bearing sleeves 56 and 56' that are carried by the upper and lower members 35 and 34. In addition to being rotatably mounted with respect to the arm portions 52b, the shaft 57 is secured with respect to the housing 33 by a latch key 55 and bolt 55a. The bolt 55a threadably projects into the lower member 34 while the key 55 projects laterally into a groove in the shaft 57.

The saddle member 52 (see Figure 5) also has an intermediate and backwardly-projecting arm portion 52c (see also Figure 4) which is pivoted by pin 60 to a pair of upper and lower links 61, and through a pin 62 to a drive arm member 63. As shown particularly in Figures 4, 6, 8 and 11, the member 63 has a collar portion 63a to rotatably receive a stub shaft 65. The shaft 65 is secured by key-latch 66 and bolt means 66a to the structure of 33 and particularly, to the upper member 35. As shown in Figure 11, inset upper and lower sleeve bearings 64 and 64' are carried by the collar portion 63a to rotatably or pivotally mount member on or about the shaft 65.

A dual-acting or two-way fluid motor 70 (see particularly Figures 4 to 6) has trunnions 70c that project vertically from its upper and lower sides and cooperates with upper and lower split collar assemblies 71 and 71' to mount the motor 70 as a unit between the upper and lower members 35 and 34 and thus, as a part of the housing 33. The bolts 71a secure the two parts of the collar assemblies 71 and 71' in position with each other. The back portion of the assemblies 71 and 71' are, as shown in Figure 5, secured as by welding to the members 35 and 34.

Fluid is exhausted and supplied alternately to flow channels or passages 70a and 70b of the motor 70 to move its piston rods 69 forwardly and backwardly as desired. The rod 69 carries a bifurcated end portion 69a that has a toggle adjustment 69b. Headed pin 68 pivotally secures 69a to a side portion of the actuating arm member 63.

In operation, when as shown in Figure 6, the piston rod 69 is withdrawn within its motor 70 by the application of positive fluid pressure to the passage 70a and the utilization of passage 70b as for exhaust, then the jaws 48a and 50a are in their open position with respect to each other. It will be noted that this opening is effected by the swinging action of saddle 52 on pivot shaft 57 while being actuated through links 61 and actuating arm member 63. The member 63 is, in turn, actuated about its pivot shaft 65 by the piston rod 69. When the piston rod 69 is moved to its extended position of Figure 4 by applying positive fluid pressure to passageway 70b and exhausting fluid from 70a, then the relative positions of the members 52, 61 and 63 is, as shown in Figures 4 and 5.

Referring particularly to Figures 5 and 7, it will be seen that the jaws 48a have an inwardly offset or slotted portion 48c which receives finger portions of the jaws 50a of the swing pair. When the jaws are moved to a closing relationship with each other, an interleaving, overlapping or cross-over fit between their fingers (see Figure 4) is provided to more positively hold the tube or lance 12 in the position of Figure 7 and in a more accurately aligned relationship within the converter vessel 13.

In addition to making the apparatus fully accessible by placing platforms on its side deck structures 20 and 23, a greatly improved clamping action is obtained to more positively grip the lance 12. The clamping areas have been spread apart as to the jaw pairs that move into and out of a cooperating relationship with each other. One side 49 of the clamp apparatus is adjustable to pro-

vide equal clamping at its top and bottom portions. The supporting structure for the clamping apparatus which includes heads, levers, links and operating arms, as well as the motor housing or cylinder, is adjustable in all directions, so that the lance 12 may be within an area of about six inches radius in its clamped position. The construction provides a somewhat universal adjustment in all directions.

Although, for simplified description, I have not in this application specifically disclosed automatic means for actuating the motor 70 for the pair of swing or pivot jaws 50a, it will be apparent that an electric fluid system may be employed, such as disclosed in Figure 8 of the drawings of my co-pending application. That is, the lance 12 may, as shown in such co-pending application, have a projecting ledge which, when it is in a proper relationship with a trip means, will actuate the system to close the pairs of jaws with respect to each other to guide and clamp the lance 12 along faces 48b and 50b of the jaw pairs. Also, if desired, such a system may be employed to raise and lower the lance 12 as suspended from its bail 73 (see Figure 2), and to open the jaws before the lance 12 is to be raised out of position from within the vessel 13.

What I claim is:

1. An improved apparatus for clamping a vertical tube member and aligning it with respect to the mouth of a vessel which comprises, a support structure adapted to project outwardly above the vessel, vertically spaced-apart pairs of cooperating clamping jaws carried on said support structure, a head operatively carrying one jaw of each pair for relative movement into and out of an interleaving relationship with respect to the other jaw of the same pair, said head having means to adjust the alignment of the one jaw with the other jaw of each pair and securely hold them in the adjusted relationship, arm portions pivotally carrying opposite vertical portions of said head on said support structure, and operating mechanism adjustably carried on said support structure and operatively connected to said head substantially centrally thereof with respect to said arm portions.

2. An improved apparatus for clamping a vertical tube member and aligning it with respect to the mouth of a vessel which comprises, a support structure adapted to project outwardly above the vessel, vertically spaced-apart pairs of cooperating clamping jaws carried on said support structure, a head pivotally carrying one jaw of each pair for relative movement into and out of an interleaving relationship with respect to the other jaw of the same pair, a saddle member pivotally-adjustably mounted on said head, a pair of vertically spaced-apart integral arms pivotally carrying said saddle member on said support structure, and actuating mechanism positioned on said support structure and operatively connected to said saddle member to swing said head and thus swing the one jaw of each pair into and out of an interleaving relationship with the other jaw thereof.

3. A clamping swing jaw construction which comprises, a pair of spaced-apart jaw members, a crosshead pivotally supporting said jaw members with respect to each other, a saddle member pivotally mounted on said crosshead and projecting therefrom, means adjustably positioned between said crosshead and said saddle member to securely hold said saddle member in an adjusted position with respect to its pivot mounting, an actuating motor, and means operatively connecting said motor through said saddle member to swing said jaw members into and out of a clamping relationship.

4. A clamping jaw construction which comprises, a support platform, a pair of vertically spaced-apart jaws mounted on said platform and having offset portions, a second pair of vertically spaced-apart jaws pivotally mounted on said platform and having offset portions that are substantially complementary with offset portions 75 of said first-mentioned pair to interfit therewith and

clamp about an article to project the article therefrom in a vertically-extending and aligned relationship, a cross-head for said second pair of jaws, said second pair of jaws being pivotally mounted on opposite end portions of said crosshead, an operating saddle pivotally mounted on said crosshead and having means securely holding it in an adjusted relationship as to its pivot mounting, and actuating means operatively connected through said saddle and crosshead to said second pair of jaws to move them into and out of a cooperating relationship with the first-mentioned pair of jaws.

5. A clamping jaw construction which comprises, a support platform, a pair of vertically spaced-apart jaws mounted on said platform and having offset portions, a second pair of vertically spaced-apart jaws pivotally mounted on said platform and having offset portions that are substantially complementary with the offset portions of said first-mentioned pair to interfit therewith and clamp an article in a vertically-extending relationship therefrom, actuating means operatively connected to said second pair of jaws to move them into and out of a cooperating clamping relation with said first-mentioned pair, a secondary platform positioned on said first-mentioned platform, and said second pair of jaws and said actuating means and operating connections therebetween being

10
15
20
25

mounted on said secondary platform, and means to adjust such secondary platform laterally and pivotally with respect to said first-mentioned platform.

6. An improved clamping construction which comprises, a mounting platform, a pair of spaced-apart jaws secured on said platform, a second pair of spaced-apart jaws swingably mounted with respect to said platform to cooperate with said first-mentioned jaws, a second platform adjustably mounting said first-mentioned platform for sliding movement with respect thereto, a third and base platform pivotally mounting said second-mentioned platform, operating and supporting connections for said second pair of jaws carried by said first platform, and means on said first platform for actuating said second pair of jaws through said operating and supporting connections.
